[57] **ABSTRACT**

The surface of a workpiece is rapidly abraded by a fast moving abrasive belt trained over a contract drum and against which the workpiece is forcefully engaged. The workpiece is carried on a work support that rotates on an axis near and transverse to that of the drum and which intersects the drum intermediate its ends. The work support has feeding and retracting motion substantially parallel to its axis, and feed force is applied to it in one embodiment of the invention by an elastic biasing medium from which stored mechanical energy is released during feed; in another, the feed force is produced by controlled rotation of jack screws, and in still another embodiment of the invention, the feed force is provided by hydraulic pressure governed by a spring-biased pressure-responsive control valve. Feed rate control is also incorporated in the machine to adapt it to use on interrupted surfaces and to different materials.

METHOD OF AND APPARATUS FOR RAPIDLY ABRADING METAL WORKPIECES

This application is a continuation of application Ser. No. 242,111, filed Apr. 7, 1972, (now abandoned), which application is in turn a continuation-in-part of application Ser. No. 181,474, filed Sept. 17, 1971 (now abandoned), which in turn is a continuation-in-part of application Ser. No. 38,431, filed May 18, 1970 (now abandoned).

The invention presented herein relates generally to the abrading or grinding art, and has as its purpose to provide a method and apparatus for rapidly machining metal workpieces to a prescribed dimension. The machining is done by feeding the workpieces against an endless abrasive belt supported by a contact drum. Hence the apparatus of this invention in some respects resembles a wide belt sander such as those used to prepare wood panels for finishing.

However, in the method and apparatus of this invention, the manner in which the workpieces are fed against the abrasive belt differs radically from that employed in belt sanders. In this respect, the present invention, at least in one embodiment thereof, takes advantage of a recent discovery that if a metal workpiece is engaged under substantially high feed force against a powerfully driven fast moving suitably supported abrasive belt, material can be removed from the workpiece at a rate unmatched by other known machining methods. For example, within an interval measured in seconds, as much as one-eighth of an inch can be abraded off a cast iron surface having an area of about 30 square inches; and this is accomplished moreover, without significantly heating the workpiece, despite the fact that the abrading is done dry.

It is the general object of this invention to provide a method and apparatus by which this new machining technique can be utilized in a practical commercially feasible manner.

In general, the invention accomplishes its purpose and object by providing a rotatable work support which is mounted towards and from the contact drum-supported abrasive belt, such feeding and retracting movement being effected radially with respect to the contact drum and with the rotational axis of the work support passing through the contact drum intermediate its ends and near and transverse to the contact drum axis. The workpiece is attached to the work support either mechanically or by a magnetic chuck. While the work support is rotating, it is pressed against the abrasive belt with substantial force, and an important feature of the invention resides in the manner in which work feeding motion and the necessarily high feed force are imparted to the rotatable work support. In one embodiment of the invention this is done by the release of mechanical energy stored in an elastic biasing medium arranged to react between the work support and a part of the machine that has a rigid connection with the fixed axis of the contact drum, and which biasing medium is a closed air chamber having resiliently deformable walls.

In another embodiment of the invention which is part of the disclosure warranting the continuation-in-part status of this application, the feed force applied to the work support is produced by controlled rotation of a group of jack screws and is applied through a closed elastic walled air chamber, and in still another form of

the invention the feed force is derived from hydraulic pressure governed by a spring biased pressure responsive control valve.

An important object of the embodiments of the invention first disclosed in the continuation-in-part application Ser. No. 181,474, is to provide an adjustable control of the feed rate and to maintain the selected feed rate constant despite interruptions in the surface being abraded.

With these observations and objectives in mind, the manner in which the invention achieves its purpose will be appreciated from the following description and the accompanying drawings which exemplify the invention, it being understood that such changes in the precise method of practicing the invention and in the specific apparatus disclosed herein may be made as come within the scope of the appended claims.

The accompanying drawings illustrate several complete examples of the embodiments of the invention constructed according to the best modes so far devised for the practical application of the principles thereof, and in which:

FIG. 1 is a somewhat simplified perspective view of a machine embodying this invention;

FIG. 2 is a front view of the machine with parts thereof broken away;

FIG. 3 is a side view of the machine, also with parts broken away and in section;

FIG. 3A (on sheet 5) is a detail view illustrating part of the structure by which the contact drum is supported;

FIG. 4 is a horizontal sectional view through FIG. 3 on the plane of the line 4-4;

FIG. 5 is a vertical sectional view through FIG. 4 on the plane of the line 5-5;

FIG. 6 is a plan view of the structure shown in FIG. 5, taken on the plane of the line 6-6 therein;

FIG. 7 is a vertical sectional view through FIG. 6 on the plane of the line 7-7;

FIG. 8 and 9 are detail views illustrating in an exaggerated form one way of storing or introducing mechanical energy in the elastic biasing means, and how the release thereof imparts work feeding motion to the rotatable work supports of the machine;

FIG. 10 is an exploded perspective view of the rotatable work supports and the structure upon which they are mounted;

FIG. 11 is a horizontal sectional view through FIG. 5 on the plane of the line 11-11;

FIG. 12 and 13 are views similar to FIGS. 8 and 9, illustrating a modified way in which mechanical energy can be stored in the elastic biasing means and released to provide a feed force by which the work supports are forced towards the contact drum;

FIGS. 14-17 are more or less diagrammatic view showing how tilting adjustment of the contact drum axis with respect to the plane of the work support can effect the flatness of the ground surface of the workpiece;

FIG. 18 is a side view of a machine embodying the invention in a form that distinguishes from the machine of FIGS. 1-11 principally in the disposition of the abrasive belt and in the fact that the rotatable work support swings from a horizontal loading position — in which position it is shown in this FIG. 18 to a vertical working position;

FIG. 19 is a view similar to FIG. 18, but showing the rotatable work support in its vertical working position;

FIG. 20 is a top plan view of the machine as shown in FIG. 19;

FIG. 21 diagrammatically illustrates the manner in which hydraulically produced feed force is applied to the rotatable work support and the rate of the work advance hydraulically controlled;

FIG. 21a is a fragmentary detail view illustrating mechanical feed rate control of hydraulically produced work feed;

FIG. 22 is a top plan view of a modified form of the machine of FIGS. 18-20, by which a workpiece can be successively presented to two abrasive belts of different grit size supported and driven by the same contact drum, without removing the workpiece from the rotatable work support;

FIG. 23 is a top plan view of the work supporting structure of still another modified embodiment of the invention wherein there are three rotatable work supports on a turntable by which each work support is indexed from a loading position successively to a rough grinding belt and a finish grinding belt;

FIG. 24 is a side view of part of the structure shown in FIG. 23, said view being taken on the plane of the line 24-24 in FIG. 23;

FIG. 25 is a more or less diagrammatic side view of a machine embodying the dual abrading station feature shown in FIG. 22 in another way; and

FIG. 26 is a top view of the work supporting structure of the machine shown in FIGS. 1 through 11 illustrating an improved version thereof in which the workpiece is swung back and forth under the contact drum-supported abrasive belt as it is ground.

The drawings illustrate a machine which embodies the apparatus aspect of the invention and by which the method of the invention can be practiced, which machine in all embodiments of the invention illustrated, has a work supporting and feeding section 5 and an abrading section 6. The abrading section comprises an endless abrasive belt 7 and drums or rollers 8 and 9 over which the belt is trained. The roller 9 is a contact drum that supports the belt against the force with which the work is fed against the belt.

The abrading section in the machine, illustrated in FIGS. 1 through 17, extends perpendicularly upwardly from the work supporting and feeding section 5, and the drums 8 and 9 over which the abrasive belt is trained are spaced apart vertically, with the contact drum lowermost. It will be understood, however, that the abrasive belt could have an orientation other than vertical, provided that the work supporting and feeding section retained the same general relationship to it as that illustrated. In fact this is the case in the embodiment of the invention illustrated in FIGS. 18-21 wherein the abrading belt is horizontally oriented.

Confining the description to that embodiment of the apparatus aspect of the invention shown in FIGS. 1-17, the two sections 5 and 6 of the machine are mounted in a main frame 10 which is a rigid weldment adapted to set squarely upon the floor and which has opposite upright side walls 12 and 13. The part of the main frame that houses the abrasive belt 7 includes a horizontal beam 11 which is anchored at one end to the side wall 12 and projects, cantilever fashion, towards the opposite side wall 13.

Both drums 8 and 9 are rotatably supported by the beam 11. The lower contact drum 9 is journaled in bearings 14 fixedly suspended from the underside of the beam. The drum 8 is journaled in bearings 15 on a yoke-like frame 16 that is supported by the beam 11 for limited up and down belt tensioning adjustment and for oscillation about a vertical axis which intersects the axes of the two drum medially between the ends thereof. Belt tensioning adjustment of the yoke 16 is effected conventionally by means of a pneumatic cylinder 17 coaxial with the axis about which the yoke and the upper roll thereon oscillate.

Oscillation is imparted to the yoke 16 by a constantly reciprocating motor 18 which may be a pneumatic cylinder fixed to the beam 11 with its piston connected to an arm 19 that extends downwardly from the yoke. Such oscillation, as in U.S. Pat. No. 3,118,314 causes the belt to shift back and forth along the length of the rolls with a view toward achieving more uniform belt wear.

Through an access opening 20 in the side wall 13 of the main frame, normally closed by a hinged door 21, the belt 7 may be placed onto or removed from the rolls 8 and 9. For belt replacement the belt tensioning means 25 must be actuated to lower the upper roll 8 and a hinged supporting arm 22 must be swung outwardly to an inoperative position clear of the opening 20. In its operative position, the arm 22 snugly engages a stud 23 that projects from the outboard end of the beam 11 to rigidly support the beam and thus assure that the contact drum 9 will be firmly supported for rotation about an axis fixed with respect to the main frame of the machine.

As best seen in FIGS. 3 and 3A, end of the supporting arm 22 is hinged to the wall 13 of the main frame at one side of the opening 20, as at 24, and its free end is detachably secured to the wall 13, at the opposite side of the opening 20, by suitable coupling means 25. Medially of its ends, the arm 22 has a pair of upper and lower vice jaws 26-27 between which the stud 23 that projects from the beam 11 is gripped. The jaws 26-27 are slidably mounted for limited vertical motion. The lower jaw is raised and lowered by a hydraulic cylinder 28 and the upper jaw is held against upward motion by an adjusting screw 29.

Obviously, for the stud 23 to be received between the jaws 26-27 when the hinged supporting arm 22 is swung to its operative position, the jaws must be separated sufficiently, but with the arm 22 in its operative position and solidly secured by means of the coupling means 25, the lower jaw can be raised by its hydraulic cylinder to clamp the stud 23 between the jaws.

As will be readily understood, adjustment of the screw 29 enables the outboard end of the beam 11 to be held at any selected elevation within a narrow range permitted by deflection of the beam. Thus the axis of the contact drum can be set to be exactly horizontal, or to be inclined slightly in one or the other direction for a purpose to be later described.

As best seen in FIG. 2, the abrasive belt is driven by a powerful electric motor 30, the shaft of which is drivingly connected with the contact drum 9 through a multiple sheave drive transmission 31. As viewed in FIG. 3, the contact drum and hence the abrasive belt travels in the clockwise direction so that during operation of the machine the material abraded from a workpiece fed against the underside of the contact drum-

supported abrasive belt is thrown rearwardly towards an outlet opening 32 in a rear wall of the frame. The abraded material passes through the opening 32 into a conventional cyclone-type separator, indicated generally by the numeral 33, which discharges it into a receptacle 34.

Located in the lower section 5 of the machine is a work supporting and feeding mechanism, designated generally by the numeral 35, which enables full utilization of the discovery that a large amount of material can be very rapidly removed from a workpiece by a fast moving, powerfully driven abrasive belt, without incurring a significant temperature rise in the workpiece, provided sufficient feed force is employed.

The work supporting and feeding mechanism 35 comprises, in general, a pair of rotatable work holding turrets 36, mounted on a turntable 37 which is in turn carried by an elevatable frame structure or platform 38. Four jack screws 39, located at the corners of the platform 38, support the platform and provide means for imparting vertical translation to the platform and all structure supported thereon. The jack screws are rigidly fixed at their lower ends to the main frame of the machine. Rotatable nut members 40, threaded onto the jack screws, are confined against axial motion relative to the platform 38 in cages 41 fixed to the underside of the platform; hence simultaneous rotation of all of the nut members raises or lowers the platform, depending upon the direction of their rotation.

As shown in FIG. 11, the four nut members are drivingly connected with one another to rotate in unison. For this purpose, the nut members have worm and worm wheel driving connections 42 with cross shafts 43 and 44, and the shafts are drivingly connected by a chain and sprocket connection 45. One of the shafts, specifically the shaft 43, is power driven by a reversible hydraulic motor indicated at 46 in FIGS. 3 and 4.

The turntable 37 is freely rotatably mounted on the platform 38 by means of a large diameter thrust bearing 47, and is rotated by a motor 48, preferably of the hydraulic type, which is mounted at the underside of the platform 38 (see FIG. 5). A positioning device 49 (FIG. 4) releasably locks the turntable in either of two positions of its rotation, in each of which one of the turrets 36 is in an operative position directly under the contact drum and the other turret is at a loading and unloading station, 180° removed from the operative position. The motor 48 of course rotates the turntable through 180° between abrading operations to interchange the positions of the turrets.

As will be evident from the description thus far, jack screw produced elevation of the platform can bring the turret that is in its operative position under the contact drum to a level at which a workpiece on the turret will contact the abrasive belt. Such jack screw produced elevation could also provide the feed force and advance the workpiece during the abrading action, but since the machine of FIGS. 1-17 is designed to do plunge grinding wherein the rate of workpiece advance is determined solely by the rapidity with which stock is removed from the workpiece, the work feeding motion is produced by the releases of mechanical energy stored in an elastic energy storing device to be later described.

During abrasion, the turrets — and hence the workpieces thereon — rotate about the axes of the turrets. (The manner in which rotation is imparted to the tur-

rets will be described later). Hence, in the absence of yieldability in the application of the feed force on the turrets, any transient high spot on the surface of a workpiece would cause a sharp rise in feed force as it was carried into engagement with the abrasive belt by rotation of the turret. Also the inevitable irregularities in the surface of the workpiece would cause corresponding fluctuations in feed force.

Bearing in mind that a uniform extremely high feed force is essential to successful rapid machining of metal workpieces by the plunge technique employed in the practice of this form of the invention, the workpieces must be fed against the abrasive belt in a way which assures the required uniformity in feed force. This is accomplished by yieldingly supporting the turrets on the turntable through compressible elastic biasing means 50 interposed between the turntable and hinged arms 51 on which the turrets are mounted for rotation about their axes.

As best seen in FIG. 10, a pedestal 52 rises from the turntable, at the top of which there are two axially spaced bearings 53 to which the arms 51 are connected. Each of the arms has a pair of axially aligned bored lugs 55, and hinge pins 56 received in the lugs 55 and bearings 53 provide the connections between the arms and the turntable. When the turntable is in each of its operative positions, the common axis of the hinge pins 56 is substantially parallel to the axis of the contact drum, and the arm 51 that is beneath the drum can therefore swing toward and from the contact drum axis.

The turrets are freely rotatably mounted on the hinged arms 51 by combination thrust and radial bearings 57. A drive shaft 58 is concentrically fixed to each turret and projects downwardly into a cavity 59 in the underside of its hinged arm, where a worm wheel 60 fixed to the shaft meshes with a worm 61 to impart rotation to the turret. The worms are driven by hydraulic motors 62 mounted on the hinged arms, as best seen in FIG. 6.

Preferably, each turret comprises a lower disc 63 which is press fitted onto its shaft 58 and an upper disc 64 which is detachably secured to the lower disc and which provides for securement to the turret of workpieces to be machined. Thus the upper disc, which provides the top face of the turret, can incorporate a magnetic chuck; or have tapped holes in it, as shown in FIG. 7, to adapt it for the mounting of a mechanical chuck.

A convenient feature of the turret is its provision for bringing lubricant to the bearing 57 which carries the turret itself and the bearing 59' in which the drive shaft of the turret is journaled, as well as to the worm and worm wheel in the cavity 59. This detail is shown in FIG. 7 and comprises a capped bore 65 in the upper disc of the turret, leading downwardly to the bearing 57, and a clearance space 66 between the underside of the lower disc 63 of the turret and the top of the hinged arm, which clearance space opens to the bearing 59' and, through it, to the cavity 59 in which the worm and worm wheel are located.

As noted hereinbefore, there is interposed between each hinged arm 51 and the turntable an elastic energy storing device 50 which consists essentially of a closed air chamber having resiliently deformable walls 67, functioning in the manner of an "air spring" like those employed in automobiles in lieu of mechanical spring

suspensions. The air chamber as illustrated is a generally cylindrical rubber bag axially short and having a flat wall 68 closing one of its ends and a radially inwardly directed flange 69 at its opposite end. The flat wall 68 is secured to the underside of a hinged arm by being clamped between a disc 70 that is removably secured to the arm and a ring 71 that is inside the bag and drawn tightly against the disc 70 by screws 72.

The inwardly directed flange 69 is secured to the top of the turntable with an air tight connection, being clamped between the turntable and a ring 73 that is drawn down onto the flange by screws 74. A hole 75 through the turntable opens into the bag, and a pressure line 76 connected to this hole provides means for introducing into the bag any desired amount of pressurized air. Obviously, pressure manifested in the bag provides a source of energy by which the hinged arm, and hence the turret thereon, are biased upwardly. This upward bias, unrestrained, is employed to provide a uniform feed force by which a workpiece is pressed against the abrasive belt.

A positive limit is established for the upward motion imparted to the hinged arm and the turret thereon by the energy stored in the air chamber. For this purpose there are a pair of tension rods 77 depending from lugs 78 on the hinged arm and loosely received in cylinders 79 that are pivotally anchored, as at 80, to the turntable. Each of the rods 77 has an enlarged head 81 on its bottom end which collides with the upper end wall 82 of its cylinder 79, as diagrammatically illustrated in FIG. 9. Such collision establishes the upper limit of swinging motion of the hinged arm, at which the top face of the turret thereon is perfectly horizontal. (It will be recalled that the axis of the hinged mounting of the arm is exactly horizontal.)

Since the feed force with which the workpiece is pressed against the contact drum-supported abrasive belt is a function of the pressure in the air chamber, and since different materials require different feed forces, the pressure in the air chamber must be adjustable. This is easily accomplished by metered introduction of air into the chamber, which can be done in any conventional manner as by connecting the air chamber pressure line 76 with an air pressure supply, through a three-way control valve 83, as suggested in FIG. 7.

OPERATION

The operation of the machine illustrated in FIGS. 1 through 17 as one embodiment of the invention, in its apparatus aspect, constitutes one way of practicing the method of this invention. That operation will now be described, and the description will proceed from the assumption that the pressure of air in the air chambers under both work holding turrets 36 is correct for the particular metal of which the workpieces are formed. It should also be understood that the unfinished surface of the workpieces to be machined, i.e., abraded, is substantially flat and uninterrupted and to avoid unnecessary complications, it will be further assumed that each workpiece is so shaped that its surface to be abraded will be substantially parallel with the top of the turret when it is simply placed thereon.

The machine is set or adjusted to the size of the workpieces by placing a workpiece on the turret that is in the loading and unloading position, and then indexing the turntable to bring the workpiece under the contact drum. This is of course done with the turntable at a

level low enough to preclude contact between the workpiece and the abrasive belt. With the workpiece under the contact drum, the turntable is elevated by powered but slow actuation of the jack screws until the top of the workpiece just "kisses" the abrasive belt, which of course should be running. This establishes datum level for the particular workpiece.

The turntable is then again indexed, and in this connection it should be noted that turntable rotation can be always in one direction or can be alternately clockwise and counterclockwise, but in each instance the rotation between indexings is 180°.

The control for the jack screw-nut driving motor 46 is now set for the desired depth of cut, which may be as much as 0.125 of an inch. This setting is made relative to the datum level determined as explained above; and when it is made, each subsequent elevation of the turntable by the jack screws will raise the turntable and the axis about which the hinged turret carrying arms swing by an amount equal to the depth-of-cut setting, and each lowering of the turntable will of course bring it back down to the datum level.

Then, with the turntable at datum level a workpiece is placed on and secured to the turret at the loading and unloading station, either by a mechanical or a magnetic chuck. Preferably the piece is so positioned that the area of the surface to be abraded is fairly well centered with respect to the turret axis. The drive motor for the loaded turret is started, and then the turntable is indexed, either manually or automatically, to bring the loaded turret under the contact drum.

Now the motor 46 begins to rotate the nut members 40 about the jack screws to elevate the rotating turret through the predetermined depth-of-cut distance and thereby forcefully feed the workpiece against the abrasive belt. This mechanical elevation of the turntable is of course positive and practically instantaneous since the nut members are driven at a fast rate. Hence the engagement of the workpiece with the contact drum-supported abrasive belt forces the turret and its hinged arm down, as shown in FIG. 8. This "loads" the elastic biasing medium, i.e. the closed air chamber, increasing by a predetermined amount the energy stored therein.

The pressure in the air chamber (elastic biasing medium) presses the workpiece against the curved abrasive surface of the contact drum-supported abrasive belt with a selected feed force which is uniformly manifested across the entire area of contact between the abrasive belt and the workpiece. That area of contact or interface will of course depend not only upon the size of the workpiece but also upon the depth of the cut that is made in the workpiece surface as it rotates with the turret. In any event, the area of contact and hence the zone of action extends along a narrow band that is parallel to the axis of the contact drum and also to the hinge axis of the arm that carries the turret.

In one or two revolutions of the turret the entire area of the workpiece surface will be machined or abraded down to the predetermined depth of cut. At this instant further upward feeding motion will be stopped by the positive limit imposed upon upward motion of the hinged arm with respect to the turntable, as shown in FIG. 9.

The speed of rotation of the turret is now automatically increased to a rate considerably faster than that employed during the stock removal phase of the opera-

tion. Although there is practically no feed force manifested at the interface between the workpiece and the abrasive belt, the high speed rotation improves the smoothness of the workpiece surface, since by this operation any minute high spots will be cut down. Upon completion of the high speed rotation of the turret, the jack screws are actuated to lower the turntable back to datum level.

During the time the described abrading operation is taking place, all under automatic control, another similar workpiece is loaded onto the other turret, so that the next cycle can be started with an index of the turntable.

In the procedure just described, the energy stored in the elastic biasing means, i.e. the closed air chamber, is increased by a predetermined amount (that is, the biasing means is loaded) by the positive upward displacement of the turntable by the jack screws while upward motion of the hinged arm and the turret thereon is restrained by the engagement of the workpiece with the drum-supported belt. Loading the biasing means in this manner tends to cause mechanical wear on the jack screws and the nut members threaded thereon, as well as all of the driving mechanism for them, since jack screw actuation takes place during every cycle of the machine. To eliminate such wear, the procedure and arrangement depicted in FIGS. 12 and 13 may be employed. In this case, the jack screws are used only to set or adjust the machine to the dimensions of the workpiece, and when that is done the jack screws are no longer operated, since the turntable remains at the datum level to which it was brought in adjusting the machine to the dimensions of the workpiece.

As illustrated in FIGS. 12 and 13, the loading of the elastic biasing medium, i.e. the air chambers, is effected by forcing the hinged arms down towards the turntable to compress the air chambers. This is done by hydraulic motors 84, as shown in FIG. 12, one for each arm. In each case the cylinder 85 of the motor is connected with the swinging arm, while its piston 86 is connected with the turntable. Hence, when hydraulic pressure fluid is fed into the cylinder 85 the workpiece is lowered sufficiently to permit its being brought under the contact drum-supported abrasive belt as the turntable is indexed. The pressure fluid fed to the hydraulic motor 84 is then allowed to escape, whereupon the hinged arm and the turret thereon is forced upward by release of the energy stored in the air chamber, feeding the workpiece against the abrasive belt. If desired, the escape of the pressure fluid from the hydraulic motor can be metered, as by an adjustable flow control valve 87 in the pressure line leading to the motor, but for plunge grinding the escape of pressure fluid from the motor should not be restricted to the point at which it interferes with the required feed force.

Elevation of the turret is arrested by the bottoming of the piston 86 in the cylinder of the hydraulic motor, which takes place when the workpiece has been abraded to the desired level.

In other respects, the apparatus and procedure depicted in FIGS. 12 and 13 is the same as that previously described; although it will be noted that the turntable datum level adjustment is made with the air chambers compressed, and therefore the datum level corresponds to the level to which the workpiece surface is to be abraded, rather than to the level of the unfinished sur-

face on the workpiece, as in the first described embodiment.

Another way of using an air chamber as an elastic biasing medium that provides the feed force by which workpieces are urged against the abrasive belt requires that a source of air under high pressure be connected with the air chamber through suitable valving. With such an arrangement each rotary turret, with a workpiece thereon, is brought to its operative position under the contact drum while the air chamber is sufficiently collapsed so that the workpiece does not contact the abrasive belt. Pressure air is then introduced into the chamber to expand it and force the workpiece against the abrasive belt. Between abrading operations air would have to be released from the air chamber until it was again "flat" enough to allow the turret to be at a level at which the workpiece could be moved to position under the drum-supported abrasive surface without contacting it. If necessary, a yieldable collapsing force could be applied to the air chamber to assure the turret being at the indicated low level. But of course such collapsing force would have to be light enough not to prevent expansion of the air chamber to the full extent needed to bring the turret to the elevation defined by the positive stop means 82 that limits upward swinging movement of the hinged arm carrying the turret.

A conventional three-way valve, such as that shown at 83 in FIG. 7, can be employed to control the pressure in the air chamber.

EFFECT OF ADJUSTING ELEVATION OF OUTBOARD END OF BEAM 11

As explained hereinbefore, the beam 11 that carries the entire abrasive unit is a rigid part of the machine frame, but it is capable of some vertical deflection. Through coaction between the hydraulic cylinder 28 and the adjusting screw 29 the outboard end of the beam can be raised or lowered a slight amount and can be secured at a selected elevation. By this adjustment, therefore, the axis of the contact drum can be brought to and held in an exactly horizontal orientation, as shown in FIG. 14, and hence can be established exactly parallel to the axis about which the turret carrying arms 51 swing. With the drum axis so oriented, the narrow elongated zone of cutting or abrading action would also be truly parallel to the axes of the contact drum and of swinging motion of the arms 51. Under these circumstances, it could be assumed that the abraded surface of the workpiece would be accurately flat. That assumption is not correct — at least in situations where the surface to be abraded is continuous across its entire area, as in the case of a solid disc.

It has been discovered that with the contact drum axis so adjusted the abraded continuous surface is slightly conically concave, as illustrated with some exaggeration in FIG. 15. The center of the conical concavity is at the center of rotation of the workpiece, which is of course at the axis about which the turret turns. Undoubtedly the concavity results from the fact that the work zone extends across the workpiece like a diametrical stripe across a circular disc, so that as the workpiece rotates, points on its peripheral portions alternately pass into and out of the work zone, whereas its central portion remains continuously engaged with the belt and therefore sustains a greater amount of abrasion.

By slightly lowering the outboard end of the beam 11, as shown in FIG. 16, or by raising it, the contact drum axis will be correspondingly tilted. As a result, one-half of the abrasive belt will do more abrading than the other half, and as points on the peripheral portions of the workpiece pass under the low side of the belt, they will be abraded at a rate fast enough to compensate for the intervals during which they are outside the work zone. The conical concavity of the abraded surface will thus be eliminated and, instead, true flatness can be achieved, as shown in FIG. 17.

An additional bonus that is gained by slightly deflecting the contact drum axis from the horizontal is that there will be more uniform wear across the width of the belt, inasmuch as the portion of the belt that crosses the rotational center of the workpiece will not be subjected to more rapid wear than other portions thereof. Hence longer belt usage can be obtained with a belt having given wear characteristics.

Since the workpieces, when placed on a turret, usually have the area of their surface to be abraded substantially centered with respect to the axis about which the turret rotates, the movement of the workpiece into and from the abrasion zone at one side of the turret axis will be upstream with respect to the travel of the abrasive belt and downstream at the opposite side of the turret axis. Over a period of time, this will lead to uneven wear across the width of the belt. To avoid this objection, the turrets are preferably rotated in opposite directions.

While the preceding description contemplates performing the abrading operation dry, a suitable liquid coolant can be directed into the zone of action through a row of nozzles 90, illustrated in FIG. 2, where wet abrading is necessary or desirable by reason of the nature of the work to be done or the material of which the workpieces are made. For wet abrasion the removed particle outlet 32 is closed by a suitable door, not shown, and the products of the abrading operation accumulate on the platform 38, which as shown in FIG. 10 can be provided with side walls 94 to give it a pan-shaped formation, with an outlet 95 leading therefrom to discharge the accumulated material into a suitably placed receptacle, not shown.

Although the apparatus illustrated in FIGS. 1-17 is no doubt understandable from the foregoing description, to assist in carrying the invention into practice, the following outline is given of the significant parameters of an actual machine embodying the invention and operating on cast iron workpieces having a surface area of about 30 square inches and abrading to a depth of 0.125 of an inch:

Width of abrasive belt	20 inches
Diameter of contact drum	13½ inches
Belt speed	5000-7000 f/m
Power of belt driving motor	300 H.P.
Feed force	750 lbs. per lineal inch of contact between belt and workpiece.
Feed Rate	½ Cubic inch per sec.
Speed of turret rotation	15 RPM for initial period of 3-4 seconds, followed by 90 RPM for 4-6 seconds.
Turntable indexing speed	15 RPM

MODIFIED EMBODIMENT — FIGS. 18-21

In the embodiment of the invention illustrated in FIGS. 18-21, the abrasive belt 7' is horizontally oriented with the contact drum 9' at the front end of the machine which is at the left in FIGS. 18-20. In front of the contact drum is the work supporting structure indicated generally by the numeral 100 by which the workpiece to be abraded is held against the contact drum-supported abrasive belt. This work supporting structure includes a rotatable work holding turret 36' mounted on a hinged arm 51'. Both of these units are essentially the same as their counterparts in the machine illustrated in FIGS. 1-11. Accordingly, the construction of 15 the turret and its mounting on the arm 51' is illustrated in FIG. 7. By the same token, the turret is driven by a hydraulic motor 62' in the manner shown in FIGS. 6 and 7.

The hinged arm 51' is mounted on a carriage 101 that rides on horizontal ways 102 in the main frame 10' of the machine. The carriage has spaced apart upright side walls 103 which embrace the hinged arm 51' and have the end portions of a shaft 56' journaled therein. This shaft hinged supports the arm 51' and has a second backup arm 104 fixed thereto. The arm 51' and the backup arm 104 are connected through a pair of hydraulic cylinders 105 and consequently move together between a horizontal loading and unloading position shown in FIG. 18 and a vertical working position shown in FIG. 19. Since the backup arm 104 is fixed to the shaft 56', oscillation imparted to the shaft by a hydraulic motor 106 swings the arms from one position to the other.

A pair of latches 107 pivotally mounted on the upright side walls 103 of the carriage holds the backup arm 104 in its upright position when the latches are actuated by control cylinders 108 to engage lugs 109 on the sides of the backup arm. When thus secured, the backup arm provides a solid immovable base comparable to the turntable 37 in the previously described machine, against which yieldable work feeding means can react to force the hinged arm 51' and the work supporting turret 36' towards the contact drum 9' and thereby press a workpiece on the turret against the abrasive belt.

By adjustment of the carriage 101 along its supporting ways 102, the axis about which the backup arm 104 and also the arm 51' swings can be located to assure proper positional relationship between the workpiece on the turret and the abrasive surface. This adjustment, therefore, enables the machine to handle workpieces of different thicknesses. The adjustment is effected by imparting rotation to a nut which is threaded on a screw 110 and is held against axial displacement by a cage structure 111 fixed with respect to the main frame 10'. The screw is attached to the carriage to move the same along its ways as rotation of the nut imparts endwise movement to the screw. A handwheel 112 drivingly connected with the nut through a suitable motion transmitting connection including chain and sprocket means 113 provides the means for rotating the nut.

Upon adjustment of the carriage to the position required by the workpiece thickness, the carriage is "locked" to its ways by pneumatic jacks 114, so that the carriage, for all practical purposes, becomes an immovable part of the machine frame. Accordingly, when the arms 51' and 104 are swung to their upright work-

ing positions, and the backup arm is gripped by the latches 107, the hydraulic cylinders 105 can be activated to press the workpiece against the abrasive belt with a predetermined feed force, it being understood that the cylinders react against the backup arm and apply pressure upon the hinged arm 51'.

During the grinding or abrading action, the hydraulic pressure in the cylinders 105 moves the workpiece a finite distance beyond the point at which it makes initial contact with the abrasive belt. The magnitude of that finite distance is determined by the adjustment of the carriage along its ways, since the outermost limit of motion of the arms in the cylinders 105 is fixed.

The cylinders 105 are, of course, connectible with a source of hydraulic pressure, as diagrammatically depicted in FIG. 21.

As there illustrated, the opposite ends of the two cylinders 105 are selectively connectable with a source of hydraulic pressure represented by the pump P and a tank or reservoir T by operation of a solenoid actuated selector valve 115. The head end of the cylinders is connected with one of the service ports of the selector valve by a line L1 which includes an adjustable pressure regulating valve 116, by which the maximum work feed pressure in the cylinders may be regulated. A check valve connected in a line L2 that bypasses the pressure regulating valve provides for unrestricted return of fluid from the head end of the cylinder when the selector valve is in its position to effect retraction of the work support, this being the position of the selector valve shown in FIG. 21.

The rod end of both cylinders 105 is connectable with the other service port of the selector valve through either of two pressure compensated volume control valves 117 and 118 by a line L3 when the selector valve 115 is shifted to its opposite position. The valves 117 and 118 control rate of flow from the rod end of the cylinders, the former permitting a fast flow and being in the circuit during the time the cylinders 105 bring the workpiece to its position of initial contact with the abrasive belt and the latter being the controlling factor during abrasion. It follows therefore that the setting of the valve 118 governs the rate at which the workpiece is advanced during the grinding operation.

A solenoid actuated selector valve 119 determines which of the two pressure compensated control valves is in the line; and a check valve in a bypass line L4 around the valve 117 provides for unrestricted flow to the rod end of the cylinders when the selector valves 115 and 119 are in the positions shown in FIG. 21.

As already noted, the pressure regulating valve 116, by its adjustment, sets the maximum feed force that can be exerted on the workpiece by the cylinders 105. If the surface of the workpiece being round is of uniform hardness and area, and free from transient high spots, the load resisting the force developed by the cylinders 105 will be relatively constant, but is a high or exceptionally hard spot on the work surface is encountered, the load will increase. In this event the feed force will automatically be held at the desired value because of the yieldability incorporated in the hydraulic system by the valve 116, which, as is well known, contains a spring that yields when the pressure at the outlet of the valve exceeds the magnitude for which the valve is adjusted, such adjustment being effected by selectively setting the degree of compression of the spring. This yieldability in the pressure with which the hinged arm

51' and consequently the turret 36' with the workpiece thereon is forced towards the contact drum, makes it possible with this modified embodiment of the invention — just as it is with the previously described machine — to provide the uniform extremely high feed force that is essential to the rapid machining of metal workpieces by the technique employed in the practice of this invention.

Briefly describing the operation of the machine illustrated in FIGS. 18-21 — and assuming that the carriage 101 has been brought to a position on its ways 102 that is correct for the thickness of the workpieces to be machined — the operator loads a workpiece onto the turret while it is in its horizontal loading position, and then by actuation of the appropriate control button of the control system (not shown) activates the motor 106 which swings the arms 51' and 104 to their upright working positions. The cylinders 108 which actuate the latches 107 are then pressurized, either through manual or automatic controls, to secure the backup arm 104 against displacement.

During the movement of the arms 51' and 104 to their upright working positions, the arms in the cylinders 105 are retracted as a result of the selector valve 25 115 being in the position at which the rod end of the cylinders is connected with the pressure source. Accordingly, when the arms reach their upright working position, the surface of the workpiece either just kisses the abrasive belt or is spaced a distance therefrom.

30 Rotation of the turret 36' by energization of its drive motor 62' is preferably begun before the arms reach their upright positions or at least before the workpiece touches the abrasive belt, but in any event, when the latches have secured the backup arm in place, the selector valve 115 is actuated to pressurize the closed end of the cylinders 105 and thereby force the workpiece against the abrasive belt. As in the other machine, when the limit of feed motion is reached, the speed of rotation of the turret can be stepped up to give the workpiece surface a smoother finish.

Upon completion of the high speed rotation of the turret, the hydraulic connections to the cylinders 105 are reversed to effect retraction of the turret and then the latches 107 are retracted and the motor 106 energized, but in the opposite direction, to return the arms 51' and 104 to the horizontal loading position, whereupon the machined workpiece is removed and replaced by another.

50 As in the previously described machine, the contact drum 9' is driven by a powerful motor 30'. Also, the manner in which the rolls 8' and 9' by which the belt 7' is carried are mounted, and the manner in which provision is made for removal and replacement of the belt are the same as in the other machine. Finally, though not shown, the machine of FIGS. 18-21 has provision for carrying off the abraded material whether dry or wet machining is being done.

FURTHER MODIFICATIONS—FIGS. 22-25

60 FIGS. 22-25 illustrate three different modifications of the invention, in all of which a workpiece can be subjected successively to a rough machining operation by a coarse grit abrasive belt and a finish machining operation by a fine grit abrasive belt, without disturbing the workpiece from its position on the turret to which it has been secured. In the machine shown in FIG. 22, a rough grit belt 120 and a fine grit belt 121 are disposed

in edgewise adjacent relationship and are trained over and driven by a single contact drum 123. The work supporting mechanism 124 is identical with that shown in FIGS. 18-20 except that the arms 51' and 104 are slideable along the rock shaft 56' which in this case is long enough to enable the arms to be positioned cooperatively with either of the belts, and instead of being fixed thereto the backup arm 104 is splined to the rock shaft.

In the machine shown in FIGS. 23 and 24, there are three work supporting turrets 36a, b, and c, rotatably mounted on arms 51'' that are hingedly mounted on a turntable 37' similar to the turntable of the machine of FIGS. 1-11. In one position of the turntable, two of the turrets, a and b, present the workpieces thereon simultaneously to two different grit abrasive belts, 120' and 121', both — as in the machine of FIGS. 1-11 — are vertically oriented and trained over the same contact drum 123'. (For convenience in illustration, FIG. 23 shows the top end of the belts which, of course, are supported by idler rolls.)

While the workpieces on the turrets a and b are being machined, a workpiece may be loaded onto the third turret c so that upon indexing the turntable one-third revolution, that new workpiece will be brought under the coarse grit belt 120', the workpiece on the turret a that had just been rough machined, will be moved under the fine grit belt 121' and the turret b carrying the workpiece that had just been given a finish "cut" will be moved to the loading and unloading station.

FIG. 25 illustrates the rough and finish belts 120' and 121' vertically oriented and disposed in tandem, with a single work support 130 slidably mounted on a horizontal track 131 beneath the belts to carry a workpiece from a loading position LP and present it successively to the rough and finish belts. The track 131 is adjustable up and down by means of jack screws 132 which act in unison as do the jack screws 39 in the machine of FIGS. 1-11, to bring the work support to its proper elevation as determined by the thickness of the workpiece. The work support comprises a backup unit 104' and a hinged arm 51' in all respects identical with those of the machine shown in FIGS. 18-21, except that in this instance there is no need to swing the arm 51' or the backup unit from their horizontal positions.

THE MODIFICATION OF FIG. 26

A modification of the machine illustrated in FIGS. 1-17 is depicted in FIG. 26. Structurally the machine of FIG. 26 is no different from that of FIG. 1-17, but there is one significant difference in the manner of its operation. By virtue of this difference an increase of as much as 400 percent is obtained — from 50 pieces to 200 pieces, with a single belt. This improvement results from simply slowly rocking or oscillating the turntable 37 about its axis during the abrading operation. Periodic reversal of the motor 48 which indexes the turntable, after it has indexed the same, and running the motor forward and back at a steady slow rate, accomplishes the result. The angle swept by the oscillating turntable is not critical, but good results have been gained with an angle of about 30°.

Such oscillation of the turntable shifts the turret that is under the drum-supported abrasive belt, and hence the band-like zone of contact between the workpiece and the belt, back and forth across the width of the belt

and thereby utilizes as much as possible of the full width of the belt.

Of course, to permit oscillation of the turntable, the positioning device 49 must be restrained against movement to its operative position.

Stated in method terms, this feature of the invention comprises oscillating the work support and the workpiece thereon about an axis that is parallel to and spaced from the axis about which the workpiece rotates in a direction normal to the axis of the contact drum and the band-like zone of contact between the drum-supported abrasive belt and the workpiece.

CONTROL OF FEED RATE AS WELL AS FEED FORCE

In the description of the operation of the different embodiments of the invention hereinbefore presented, it was assumed that the surface of the workpiece to be ground was continuous, so that throughout the grinding operation there was contact between the workpiece and the abrasive belt. Under those circumstances, there is no need for controlling the rate at which the work is fed against the belt; in fact, a fast plunging action with the rate of feed determined solely by the removal of the stock was most effective. It is possible, however, to operate the apparatus — in all of its various embodiments — in such a way that the rate of feed, as well as the feed force, will be controlled. This adapts the invention to the machining or grinding of interrupted surfaces — as, for instance, the faces of a number of spaced apart bosses or pads on a casting. In such instances, as the turntable rotates the workpiece, a boss or pad being ground will leave the abrasive belt before the next one to be ground contacts it. Hence, unless the feed rate is controlled, in a manner which restrains the feed force, the unrestrained feed force could project the workpiece the full predetermined distance towards the abrasive belt before the second boss or pad would reach the belt. This of course would lead to a wholly undesirable condition, and make the maintenance of uniform feed force and smooth machine operation impossible.

The desired feed rate control can be obtained in that embodiment of the invention illustrated in FIGS. 18-21 by the adjustment of the pressure compensated control valve 118 which regulates the flow out of the rod end of the cylinders 105 and thus determines the rate at which the cylinders feed the workpiece against the abrasive belt.

Another way of controlling the rate at which the cylinders 105 feed the workpiece against the abrasive belt is illustrated in FIG. 21a. In this case the arms 51' and 104 are connected by a screw 135 which is freely rotatably but not axially movably connected with one of the arms, preferably the arm 104, and has threaded engagement with a nut 136 non-rotatably connected with the arm 51'. The connection between the nut and the arm 51' precludes axial movement of the nut towards the arm 104 but permits such movement in the opposite direction so that any interference with advance of the arm 51' can be accommodated without damage to the screw and nut connection.

Feed rate is controlled through this connection by imparting slow rotation to the screw as by means of a stepping motor 137 or a suitable hydraulic motor drivingly connected with the screw through a gear reduction such as a worm and worm wheel 138.

Obviously, of course, after each grinding operation the screw would have to be driven in the reverse direction to permit the arm 51' to be retracted to its initial position, but this reverse rotation can be at a faster rate.

In the embodiment of the invention shown in FIGS. 1-11, feed rate control can be obtained by governing the speed of the motor 46 which drives the nut members 40 during elevation of the platform 38, so that instead of effecting very rapid ascent of the platform to substantially instantaneously "load" the air chamber 50, as previously described, the platform rises very gradually so that interruptions in the work surface being machined do not result in abrupt advance of the workpiece. Although the type of motor employed to elevate the platform 38 is a matter of choice, a conventional stepping motor is admirably suited for the purpose.

To maintain complete control of the feed rate the pressure in the elastic air chambers 50 should be high enough to maintain them in their maximum state of distention holding the work supports at the limit of their upward motion with respect to the platform 38 during the controlled ascent of the platform. With such pressure in the air chambers all work feeding motion is produced by the rotation of the nut members 40 about their jack screws, at least as long as the removal of stock proceeds as expected. If, however, some transient high spot or hard spot in the workpiece surface is encountered, the elastic air chamber provides a cushion to avoid the application of excessive feed force. The air chambers also guard against the consequences of some unexpected occurrence such as an incorrect adjustment in the range of motion mechanically imparted to the platform.

The presence of the elastic air chambers 50 also has the advantage of versatility since it enables using a single machine to do either plunge grinding or controlled feed rate grinding, it being understood that for plunge grinding the elevation of the platform would not be restrained except by the engagement of the workpiece with the abrading belt and until the workpiece surface had been ground to the desired level.

Not only does the provision for controlling the feed rate enable successful grinding of interrupted workpiece surfaces, but it also affords adaptability to the grinding of different materials.

In every case where feed rate control is employed, it can be governed by the control system of the machine whether it be manually operated or responsive to programmed numerical control.

Those skilled in the art will appreciate that the invention can be embodied in forms other than as herein disclosed for purposes of illustration.

The invention is defined by the following claims.

We claim:

1. The method of machining a surface of a workpiece whether interrupted or not, to a predetermined level by grinding the same with an endless abrasive belt having a stretch thereof supported against the thrust of the workpiece thereon by a backup member which engages the back side of the belt, which method comprises:

A. fixing the workpiece to a work supporting member that is rotatable about an axis that passes substantially perpendicularly through the zone of contact between the workpiece and the abrasive belt, with

said workpiece surface facing the backup member-supported abrasive belt;

B. rotating the work supporting member about said axis;

5 C. while the work supporting member and the workpiece thereon are rotating, applying to one of said members a feed force that yields upon resistance thereto in excess of a predetermined magnitude, to thereby effect relative work feeding motion between said members in the direction and in a manner to produce grinding engagement under substantially constant pressure between the workpiece and the backup member-supported abrasive belt; and

10 D. so controlling the rate of said relative work feeding motion between said members that the rate of said relative motion is unaffected by changes in the nature of the contact between the workpiece and the abrasive belt.

20 2. The method of claim 1, wherein said relative work feeding motion between said members is produced by fluid pressure cylinder means having a head end into which fluid under pressure is fed to produce said relative work feeding motion and a rod end from which fluid flows during said relative work feeding motion.

25 3. The method of claim 2, wherein the control of the rate of said relative work feeding motion is achieved by regulating the flow of the pressure fluid out of the rod end of said hydraulic cylinder means.

30 4. The method of claim 2, wherein the control of the rate of said relative work feeding motion is achieved by regulating relative rotation between a screw and nut connection, arranged to restrain the motion produced by said fluid pressure cylinder means.

35 5. The method of claim 1, wherein the backup member is fixed, and wherein said relative motion between said members is obtained by moving the work supporting member towards the backup member.

40 6. The method of claim 2, wherein the backup member is fixed, and wherein said hydraulic cylinder means reacts between the work supporting member and a point fixed with respect to the backup member.

7. The method of claim 1, wherein said backup member is a contact drum member and wherein the axis about which the work supporting member rotates is substantially radial to the axis of the contact drum.

45 8. The method of claim 7, wherein the axis about which the contact drum member rotates is fixed, and wherein said relative motion between said members is obtained by moving the work supporting member towards the contact drum member.

50 9. The method of claim 8, wherein said movement of the work supporting member towards the contact drum member is produced by steadily mechanically advancing a rigid member towards the side of the contact drum member at a uniform predetermined rate, and imparting the motion of the advancing rigid member to the work supporting member through a yieldable motion transmitting connection which does not yield as long as the feed force between the workpiece and the drum-supported abrasive belt remains below a predetermined maximum.

55 10. The method of claim 9, wherein the advance of said rigid member towards the contact drum member

is effected by relative rotation between a screw and nut,

and wherein the control of the rate at which the workpiece is fed against the abrasive belt is achieved by regulating the drive by which relative rotation between the screw and nut is produced. 5

11. The method of claim 1, further characterized by:

with the workpiece in grinding engagement with the backup member supported abrasive belt, oscillating the work supporting member about an axis parallel to the axis about which the workpiece rotates, and so located with respect to the backup member that the arc defined by the oscillatory motion of the work supporting member lies in a plane that is substantially parallel to the zone of contact between the abrasive belt and the workpiece. 10

12. The method of machining either an uninterrupted substantially flat surface of a workpiece or a plurality of spaced apart substantially flat surfaces thereof to a desired predetermined level by means of an endless abrasive belt trained over a rotatable contact drum, which method comprises:

- A. providing a rotatable work support to which the workpiece is secured;
- B. providing a yieldable feed force;
- C. by means of said yieldable feed force, effecting relative work feeding motion between the workpiece and the drum-supported abrasive belt;
- D. so governing said yieldable feed force that at no 30 time will it exceed a predetermined magnitude but will yield to any transient increase in load;
- E. while the workpiece is in contact with the drum-supported abrasive belt, effecting rotary motion of the workpiece about an axis which is normal to the substantially flat surface of the workpiece and which passes transversely through the contact drum, to bring the entire area of the surface or surfaces of the workpiece being machined into operative engagement with the abrasive belt;
- F. so controlling the rate at which said yieldable feed force effects relative work feeding motion, that regardless of discontinuity in contact between the workpiece and the abrasive belt, the rate of said relative work feeding motion remains substantially constant; and
- G. when the desired level to which said workpiece surface or surfaces is to be machined has been reached, arresting the relative work feeding motion. 50

13. The method of machining a surface of a workpiece whether interrupted or not, to a predetermined level by grinding the same with an endless abrasive belt trained about a rotating contact drum which supports the abrasive belt against the thrust of the workpiece thereon, which method comprises:

- A. fixing the workpiece to a work support that is rotatable about an axis substantially radial to that of the contact drum and passes through the drum, with said workpiece surface facing the drum-supported abrasive belt;
- B. rotating the work support about said substantially radial axis;
- C. while the work support and the workpiece thereon are rotating, effecting relative work feeding motion between the work support and the contact drum in the direction and in a manner to produce grinding 60
- 65

engagement under substantially high pressure between the workpiece and the drum-supported abrasive belt; and

D. with the workpiece in grinding engagement with the abrasive belt, oscillating the work support about an axis parallel to the axis about which the workpiece rotates, and so located with respect to the contact drum that the arc defined by the oscillatory motion of the work support is substantially parallel to the axis of the drum.

14. The method of machining a substantially flat surface of a workpiece to a desired predetermined level by means of an endless abrasive belt trained over a contact drum constrained to rotate about a fixed axis, which method includes

rotating the workpiece while in contact with the abrasive surface, about an axis normal to the axis of the contact drum, to bring the entire area of the surface of the workpiece being machined into operative engagement with the abrasive surface

and which method is characterized by:

- A. effecting a feed force between the workpiece and the contact drum-supported abrasive belt by disposing a closed chamber having resiliently deformable walls, and in which mechanical energy can be stored, in such relation to the workpiece and the contact drum that release of mechanical energy stored in said chamber produces work performing engagement between the workpiece and the contact drum-supported abrasive belt;
- B. contracting said chamber to store energy therein;
- C. releasing energy stored in said chamber by allowing it to expand to thereby yieldingly effect the desired feed force; and
- D. when the level to which the workpiece surface is to be machined is tangent to the contact drum-supported abrasive belt, arresting further expansion of the closed air chamber. 40

15. The method of machining a substantially flat surface of a workpiece to a desired predetermined level by grinding the same with an endless abrasive belt trained over a rotating contact drum which supports the abrasive belt against the thrust of the workpiece thereon, which method comprises:

- A. providing a compressible elastic walled chamber in which mechanical energy can be stored;
- B. compressing the elastic walled chamber to store a predetermined amount of mechanical energy therein;
- C. by the release of said mechanical energy in the elastic walled chamber, effecting grinding engagement and relative work feeding motion between the workpiece and the drum-supported abrasive belt;
- D. with the workpiece in grinding engagement with the drum-supported abrasive belt, rotating the workpiece about an axis which is normal to said substantially flat surface of the workpiece and which passes transversely through the contact drum, to bring the entire area of said surface into operative engagement with the drum-supported abrasive belt; and
- E. when the level to which said workpiece surface is to be ground is tangent to the curved surface of the drum-supported abrasive belt, arresting said rela- 65

tive work feeding motion between the workpiece and the drum-supported abrasive belt.

16. The method of claim 15, wherein the compression of the compressible elastic walled chamber is effected by applying hydraulic pressure upon a part connected therewith.

17. The method of claim 16, further characterized by fully releasing said hydraulic pressure to allow the energy stored in the compressible elastic walled chamber to effect unrestricted relative work feeding motion between the workpiece and the contact drum-supported abrasive belt.

18. The method of claim 1, further characterized in that successive workpieces are rotated in opposite directions.

19. A surface abrading machine of the type comprising endless abrasive belt means having a stretch thereof supported by a backup member engaging the back side of the belt means, a work supporting member upon which a workpiece is held to be abraded by said abrasive belt means and which is rotatable on an axis that substantially perpendicularly intersects the zone of contact between the workpiece and the belt means, one of said members being movable toward and from the other to provide for engagement and disengagement between the workpiece and the abrasive belt means for relative feeding motion therebetween as abrasion takes place, said machine being characterized by:

A. power drive means arranged to react between said one member and a relatively fixed part of the machine to effect relative feeding motion of said one member toward the other to thereby bring out engagement between the surfaces of the workpiece and the abrasive belt means to cause abrasion of the workpiece; and

B. means unaffected by discontinuity in contact between the workpiece and the abrasive belt means resulting from interruption in the workpiece surface being ground, for controlling the rate at which said power drive means effects said relative feeding motion.

20. The surface abrading machine of claim 19, wherein said power drive means comprises a fluid pressure responsive device connected with a source of fluid pressure,

and wherein said means for controlling the rate at which said relative feeding motion occurs comprises a flow control valve connected with said fluid pressure responsive device.

21. The surface abrading machine of claim 19, wherein said power drive means comprises a fluid pressure responsive device connected with a source of fluid pressure,

and wherein said means for controlling the rate at which said relative feeding motion occurs comprises a screw and nut connection between said one member and said relatively fixed part of the machine and arranged to resist the force produced by the fluid pressure responsive device.

22. The surface abrading machine of claim 19, wherein said power drive means comprises a screw and nut connection between said one member and said relatively fixed part of the machine,

wherein said means for controlling the rate at which said relative feeding motion occurs includes power actuated means for regulating relative rotation between the screw and nut;

and further characterized by yieldable means through which the force produced by said power drive means is imparted to said one member.

23. The surface abrading machine of claim 19, further characterized by:

means providing yieldability in the motion producing effect of the force producing means on said one member, to thereby cushion sudden increases in the feed force manifested at the engagement between the workpiece and the abrasive belt means and resulting from transient high spots in the workpiece surface and/or hard spots therein.

24. The surface abrading machine of claim 23, wherein said means for providing yieldability in the motion producing effect of said force producing means comprises:

a closed air chamber having resiliently deformable wall means and containing air under pressure, and through which said force producing means acts to effect said relative motion.

25. The abrading machine of claim 23, wherein said force producing means comprises:

a fluid pressure responsive device connected with a pressure source;

and wherein said means for providing yieldability in the motion producing effect of said force producing means comprises control valve means which is sensitive to changes in the force manifested at the engagement between the workpiece and the abrasive belt means and operable to govern connection of the fluid pressure responsive device with its pressure source.

26. The abrading machine of claim 19, wherein said backup member is a rotatable contact drum member, and further characterized by:

A. a frame structure which maintains a fixed relationship to the axis of the contact drum member during at least the final portion of the operation performed by the machine;

B. wherein said work supporting member comprises

1. an arm hingedly connected with said frame structure for movement with respect thereto about an axis substantially parallel with the axis of the contact drum member,

2. a turret having means to grip the workpiece, and

3. bearing means rotatably connecting the turret with said hinged arm; and

C. wherein said force producing means reacts between said hinged arm and said frame structure.

27. The abrading machine of claim 19, wherein said backup member is a rotatable contact drum member, and further characterized by:

A. mounting structure for the contact drum member and the rotatable work supporting member, by which said members are mounted in the relationship set forth in claim 19,

and wherein by virtue of said relationship, the work performing engagement between the workpiece and the drum supported abrasive belt means extends along a narrow zone which is substantially intersected by a plane that contains the axis of the contact drum member;

B. wherein said force producing means is yieldable and comprises a hydraulic pressure responsive device connected with a pressure source;

and further characterized by

- C. means for cushioning sudden increases in the feed force manifested at the engagement between the workpiece and the drum supported abrasive belt means resulting from transient high spots in the workpiece surface and/or hard spots therein, said cushioning means comprising control valve means which is sensitive to the force manifested by the engagement between the workpiece and the abrasive belt means and operable to govern connection of the hydraulic pressure responsive device with its pressure source.

28. The abrading machine of claim 27, further characterized by:

- means for arresting relative feeding motion between the contact drum member and the work supporting member when a workpiece on the work supporting member has been abraded to a predetermined level.

29. The abrading machine of claim 27, further characterized by:

the work supporting member comprising

1. a turret rotatably mounted on a hinged arm;
  2. means hingedly mounting said arm for swinging motion towards and from the contact drum member about a hinge axis that is generally parallel with the axis of the contact drum member;
- said mounting structure further providing for tiltable relative adjustment between said hinge axis and the axis of the contact drum member in directions parallel to said plane that substantially intersects the work zone, to enable said hinge axis and the axis of the contact drum member to be brought into true parallelism or to be inclined to one another in said directions,
- and means for effecting such tilting adjustment.

30. The abrading machine of claim 27, wherein the mounting structure further comprises means for effecting tilting adjustment of the contact drum member.

31. The abrading machine of claim 19, wherein said backup member is a rotatable contact drum member, and further characterized in that

1. said machine has a main frame in which the contact drum member is mounted,
2. wherein the work supporting member has a work supporting surface to which a workpiece may be secured,

and further characterized by:

- A. a supporting arm for the work supporting member;
- B. means rotatably mounting the work supporting member on said arm for rotation about an axis perpendicular to its work supporting surface;
- C. hinge means mounting said supporting arm for swinging motion about an axis parallel to that of the contact drum member between a lowered position in which the work supporting surface is substantially horizontal, and an upright position in which the axis of the work supporting member perpendicularly intersects the axis of the contact drum member medially of its ends;
- D. wherein said force producing means reacts between said hinged supporting arm and said relatively fixed part of the machine when the arm is in its upright position to feed a workpiece on the work supporting member against the contact drum supported abrasive belt means; and

- E. drive means for rotating the work supporting member about its axis while a workpiece thereon is being fed against the abrasive belt means.

32. The abrading machine of claim 31, wherein said hinge means comprises

1. a hinged frame member mounted to swing about the hinge axis of the hinged arm in unison with said arm, and
2. means to secure said frame member in an upright position,

and further characterized in that:

- said force producing means for imparting work feeding motion to the rotatable work supporting member comprises fluid pressure responsive means reacting between said hinged frame member and said hinged arm.

33. The abrading machine of claim 32, further characterized by:

- A. a carriage slidably mounted on the main frame of the machine for translation perpendicularly towards and from the contact drum member;
- B. wherein the common hinge axis of said hinged arm and hinged frame member is fixed with respect to said carriage so that translation of the carriage provides for adjustment of the distance between the work receiving surface of the rotatable work supporting member and the contact drum member to adapt the machine to different sized work; and
- C. means for effecting translation of the carriage;

and further characterized in that

- said means for securing said hinged frame member in its upright position comprises latch means on said carriage engageable with said hinged frame member.

34. The abrading machine of claim 19, wherein

1. said backup member is a rotatable contact drum member,
  2. wherein said endless abrasive belt means has areas of different grit size to provide for rough abrading and finish abrading,
  3. wherein said machine has a main frame in which the contact drum member is rotatably mounted,
- and further characterized by:

- A. frame structure mounted in said main frame for translation towards and from the contact drum member in directions radial thereto;
- B. wherein the work supporting member is rotatably mounted on said frame structure by means of an arm hingedly connected with the frame structure for swinging movement in directions laterally toward and from the contact drum member;
- C. bearing means mounting the work supporting member on the hinged arm for rotation about an axis normal to the axis about which the arm swings;

- D. means for bringing the rotatable work supporting member into cooperative relation with all of said different grit size areas of the abrasive belt means, so that a workpiece on the work supporting member can be successively abraded by the different grit size areas of the abrasive belt means without removing the workpiece from the rotatable work supporting member;

- E. drive means on the hinged arm drivingly connected with the rotatable work supporting member to rotate the latter; and

F. wherein said force producing means reacts between the hinged arm and said frame structure to move the hinged arm towards the contact drum member and thereby feed the workpiece on the work supporting member against one of said different grit size areas of the abrasive belt means.

35. The abrading machine of claim 34, wherein said means for bringing the rotatable work supporting means into cooperative relation with said different grit size areas of the abrasive belt means does so individually and successively,

so that a workpiece can be successively abraded by the different grit size areas of the abrasive belt means without removing it from the rotatable work support.

36. The abrading machine of claim 35, wherein the different grit size areas of the abrasive belt means are supported on and driven by a single contact drum member,

and wherein said means for bringing the work supporting member into cooperative relation individually with the different grit size areas of the abrasive belt means provides for relative displacement between the work supporting member and the contact drum member along a path generally parallel to the axis of the contact drum member.

37. The abrading machine of claim 34, wherein the different grit size areas of the abrasive belt means are supported by a plurality of contact drums that are disposed in tandem spaced parallel relationship,

and wherein said means for bringing the work supporting member into cooperative relation individually with the different grit size areas of the abrasive belt means provides for relative displacement between the work supporting member and said plurality of contact drums along a path generally normal to the axes of the contact drums.

38. The abrading machine of claim 19, wherein said backup member is a rotatable contact drum means, further characterized by:

A. a turntable mounted to rotate about a fixed axis;

B. wherein said contact drum means comprises a plurality of contact drums rotatable about fixed axes normal to the axis of the turntable with their peripheries tangent to a single plane spaced from and generally parallel to the turntable, said contact drums being equispaced from the axis of the turntable;

C. an abrasive belt being trained over each contact drum,

said belts being of different grit size;

D. wherein said work supporting member comprises a plurality of rotatable work supports, each adapted to have a workpiece attached thereto;

E. means mounting each of the rotatable work supports on the turntable with their axes parallel to that of the turntable and equispaced therefrom a distance such that upon indexed rotation of the turntable the work supports are successively brought into cooperative relation with the contact drums,

so that a workpiece on a rotatable work support can be successively fed against the different abrasive belts without removing it from the work support to which it is attached,

said means for mounting the work supports on the turntable comprising arms hinged at one end to the turntable and having the work supports rotatably mounted on the other ends thereof;

F. wherein said force producing means comprises yieldable biasing means reacting between each arm and the turntable to feed the workpiece on its respective work support successively against each of the abrasive belts with a force not exceeding a predetermined magnitude; and

G. power means for rotating the work supports while the workpieces thereon are being fed against the abrasive belts.

39. In a machine for abrading the surface of a workpiece to a predetermined level by maintaining the workpiece engaged under high force against the active surface of an endless abrasive belt trained over a contact drum rotating on a fixed axis, work feeding means for said machine comprising:

A. a frame structure which maintains a fixed relationship to the contact drum axis during at least the final portion of the abrading operation performed by the machine;

B. a work support by which the workpiece is held;

C. means mounting the work support on the frame structure for work feeding motion relative to the frame structure in a direction substantially radial to the drum; and

D. means for imparting work feeding motion to the work support, characterized by

1. a closed air chamber, certain walls of which are resiliently deformable, arranged to react between the frame structure and the work support, and

2. means for compressing said closed air chamber to thereby store a predetermined amount of mechanical energy in said chamber, the release of which imparts work feeding motion to the work support.

40. The structure of claim 39, further characterized by motion limiting means operatively connected with the movable work support and the frame structure for positively limiting the work feeding motion imparted to the work support by the release of energy stored in said closed air chamber, to provide for termination of feeding motion when the workpiece has been abraded to the predetermined level.

41. The structure of claim 39, wherein the work support is a rotatable turret; and the means mounting the work support comprises:

A. an arm hingedly connected with the frame structure for movement with respect thereto about an axis substantially parallel with the axis of the contact drum; and

B. bearing means rotatably connecting the turret with said hinged arm.

42. The structure of claim 41, further characterized by drive means on said hinged arm operatively connected with the turret to impart rotation thereto.

43. The structure of claim 39, wherein the means for compressing said closed air chamber comprises:

positive motion producing means operatively connected with said frame structure to move the same a distance towards the axis of the contact drum, which distance is determined by the depth of material to be removed in abrading the workpiece.

44. The structure of claim 39, wherein the means for compressing said closed air chamber comprises:

motion producing power means connected with said frame structure and said hinged arm and arranged to move the latter away from the drum axis and thereby compress said air chamber.

45. An abrading machine comprising:

A. a main frame;

B. a contact drum mounted in the frame for rotation about a fixed axis;

C. an endless abrasive belt trained over the contact drum;

D. a frame structure mounted in the main frame for movement towards and from the contact drum in directions radial thereto;

E. a rotatable work support adapted to have a workpiece to be ground attached thereto;

F. means mounting the rotatable work support on the frame structure for movement to and from an operative position engaging a workpiece thereon with the drum supported abrasive belt, said mounting means comprising

1. an arm hingedly connected with the frame structure for swinging movement in directions toward and from the axis of the contact drum about an axis substantially parallel with said contact drum axis, and

2. bearing means mounting the work support on the hinged arm for rotation about an axis which in the operative position of the work support passes transversely through the contact drum medially of its ends and near the axis of the contact drum;

G. means for moving the frame structure and the work support thereon to bring the same to a position in which a workpiece on the work support is spaced a predetermined distance from the contact drum, determined by the dimensions of the workpiece to be ground;

H. elastic biasing means interposed between the hinged arm and the frame structure, in which mechanical energy can be stored by relative movement towards one another between the hinged arm and the frame structure,

the release of such energy producing work feeding motion of the work support whereby a workpiece attached to the work support is fed against the drum-supported abrasive belt;

I. power means operable to effect such relative movement between the hinged arm and the frame structure; and

J. drive means on the hinged arm drivingly connected with the rotatable work support to rotate the latter.

46. The abrading machine of claim 45, wherein the power means is connected with said means for translating the frame structure and effects relative motion between said hinged arm and the frame structure by effecting motion of the frame structure toward the drum axis while a workpiece on the work support is engaged with the belt.

47. The abrading machine of claim 45, wherein said power means comprises a motion producing motor reacting between the hinged arm and the frame structure.

48. The abrading machine of claim 47, wherein said motion producing motor comprises a hydraulic cylinder and piston, further characterized by:

A. said hydraulic cylinder and piston being so arranged that pressure fluid fed to the cylinder draws the hinged arm towards the frame structure; and

B. further characterized by means for metering flow of such pressure fluid from the cylinder to regulate the rate at which energy released from the elastic biasing means effects engagement of the workpiece with the drum-supported abrasive belt.

49. The abrading machine of claim 45, further characterized in that said frame structure comprises:

A. a non-rotatable unit constrained to translation; and

B. a turntable rotatably mounted on said unit for rotation about an axis normal to the axis of the contact drum, but spaced therefrom,

1. the hinged arm being on the turntable, and

2. the axis about which the work support turns being generally parallel to the turntable axis and spaced therefrom by a distance substantially equal to the spacing between said turntable axis and the axis of the contact drum,

so that by rotation of the turntable the rotary work support can be moved between a working position in which its axis of rotation is near the axis of the contact drum and a loading and unloading position in which it is spaced to one side of the contact drum.

50. In an abrading machine wherein work to be ground is forced against the active surface of an endless abrasive belt trained over a contact drum rotating on a fixed axis, work feeding means for said machine comprising:

A. a turntable mounted to rotate about an axis normal to, but spaced to one side of, the axis of the contact drum, and for translation along its own axis of rotation;

B. an arm hingedly mounted on the turntable for swinging movement from and toward the contact drum axis, about an axis substantially parallel with that of the contact drum, by which movement the arm is carried to and from a retracted position;

C. a work carrying turret rotatably mounted on said arm and having means by which a workpiece may be attached thereto,

rotation of the turntable enabling the turret to be moved between an operative work performing position in juxtaposition to the contact drum and a loading and unloading station spaced from the contact drum;

D. means for effecting translation of the turntable to a position determined by the dimensions of a workpiece attached to the turret and at which position swinging movement of the hinged arm away from its retracted position feeds the workpiece carried by the turret against the drum-supported abrasive belt;

E. elastic biasing means reacting between the hinged arm and the turntable and in which mechanical energy is stored in consequence of hinged movement of the arm toward its retracted position,

such stored energy, when released, being available to move the arm away from its retracted position; and

F. means for rotating the turret to bring the entire area of the workpiece surface being ground into operative engagement with the drum-supported abrasive belt.

51. The abrading machine of claim 50 wherein the elastic biasing means is interposed between the hinged arm and the turntable; and

wherein the axis about which said hinged arm swings is intersected by the axis of the turntable so that said hinged arm, the turret thereon and the elastic biasing means are all located at one side of the turntable axis; and

wherein said hinged arm, the work carrying turret thereon and the elastic biasing means are duplicated at the diametrically opposite side of the turntable, so that 180° of rotation of the turntable interchanges the work carrying turrets which are respectively at the operative position and at the loading and unloading station.

52. The abrading machine of claim 51, further characterized in that the means for rotating the turrets drives them in opposite directions.

53. An abrading machine having an endless abrasive belt as its work performing element and comprising:

A. a contact drum rotatable about its axis and over which the abrasive belt is trained;

B. a rotatable work support adapted to have a work-piece attached thereto;

C. mounting structure for the contact drum and the rotatable work support, said mounting structure providing for

1. the contact drum and work support to have their rotational axes near and generally transverse to one another, with the rotational axis of the work support intermediate the ends of the contact drum, and

2. relative work feeding motion between the work support and the contact drum towards one another along a path substantially parallel to the axis of the work support to effect engagement between a workpiece on the work support and the contact drum-supported abrasive belt along a narrow work zone which is substantially intersected by a plane that contains the axis of the contact drum;

D. a closed air chamber, certain walls of which are resiliently deformable and in which energy can be stored by contraction of the air chamber, said air chamber being interposed between the work support and a rigid support so that release of energy stored therein by expansion of said closed air chamber effects relative work feeding motion between said work support and the contact drum;

E. means for contracting said air chamber to thereby store energy therein; and

F. means for rotating the work support about its axis so that a workpiece attached to the work support by such rotation will have the entire area of its surface which is to be abraded operatively engaged with the abrasive belt.

54. The abrading machine of claim 53, further characterized by:

means for limiting expansion of said closed air chamber to thereby terminate relative feeding motion between the contact drum and the work support when a workpiece on the work support has been abraded to a predetermined level.

55. The abrading machine of claim 53, further characterized by:

A. the work support comprising a turret rotatably mounted on a hinged arm;

B. said mounting structure comprising means hingedly mounting said arm for swinging motion towards and from the contact drum about a hinge axis that is generally parallel with the axis of the contact drum;

C. said mounting structure further providing for tiltable relative adjustment between said hinge axis and the axis of the contact drum in directions parallel to said plane that substantially intersects the work zone, to enable said hinge axis and the axis of the contact drum to be brought into true parallelism or to be inclined to one another in said directions; and

D. means for effecting such tilting adjustment.

56. The abrading machine of claim 54, wherein the mounting structure provides for tilting adjustment of the contact drum.

57. In a machine for abrading the surface of a workpiece to a predetermined level by maintaining the workpiece engaged under high force against the active surface of an endless abrasive belt trained over a contact drum rotating on a fixed axis, work feeding means for said machine comprising:

A. a frame structure which maintains a fixed relationship to the contact drum axis during at least the final portion of the abrading operation performed by the machine;

B. a work support by which the workpiece is held, said work support comprising

1. an arm hingedly connected with the frame structure for movement with respect thereto about an axis substantially parallel with the axis of the contact drum,

2. a turret having means to grip the workpiece, and

3. bearing means rotatably connecting the turret with said hinged arm; and

C. means for imparting work feeding motion to the work support and exerting a substantially large feed force thereon characterized by

1. yieldable force applying means arranged to react between the frame structure and the hinged arm, and

2. means comprising part of said yieldable force applying means for cushioning sudden increases in the feed force manifested at the engagement between the workpiece and the abrasive belt and resulting from transient high spots in the workpiece surface and/or hard spots therein.

58. The structure of claim 57, wherein said yieldable force applying means comprises a hydraulic pressure responsive device connected with a source of hydraulic pressure and a pressure regulating valve responsive to the pressure exerted by said hydraulic pressure responsive device to govern the magnitude of the feed force delivered by said yieldable force applying means.

59. An abrading machine comprising:

A. a main frame;

B. contact drum means rotatably mounted in the main frame;

C. endless abrasive belt means of different grit size trained over the contact drum means, to provide for rough abrading and finish abrading;

- D. a frame structure mounted in the main frame for translation towards and from the contact drum means in directions radial thereto;
  - E. a rotatable work support adapted to have a workpiece to be abraded attached thereto;
  - F. means mounting the rotatable work support on the frame structure comprising
    - 1. an arm hingedly connected with the frame structure for swinging movement in directions laterally toward and from the contact drum means,
    - 2. bearing means mounting the work support on the hinged arm for rotation about an axis normal to the axis about which the arm swings, and
    - 3. means for bringing the rotatable work support into cooperative relation with all of said different grit size abrasive belt means, so that a workpiece can be successively abraded by the different grit size belt means without removing the workpiece from the rotatable work support;
  - G. force applying means interposed between the hinged arm and said frame structure for moving the hinged arm towards the contact drum means to thereby feed the workpiece attached to the work support against one of said abrasive belt means; and
  - H. drive means on the hinged arm drivingly connected with the rotatable work support to rotate the latter.
- 60.** An abrading machine having an endless abrasive belt as its work performing element and comprising:
- A. a contact drum rotatable about its axis and over which the abrasive belt is trained;
  - B. a rotatable work support adapted to have a workpiece attached thereto and comprising
    - 1. a turret rotatably mounted on a hinged arm, and
    - 2. means mounting the hinged arm for swinging motion towards and from the contact drum about a hinge axis that is generally parallel with the axis of the contact drum;
  - C. mounting structure for the contact drum and the mounting means for said hinged arm, said mounting structure providing for
    - 1. the contact drum and the work support to have their rotational axes near and generally transverse to one another, with the rotational axis of the work support intermediate the ends of the contact drum,
    - 2. relative work feeding motion between the work support and the contact drum towards one another along a path substantially parallel to the axis of the work support to effect engagement between a workpiece on the work support and the contact drum-supported abrasive belt along a narrow work zone which is substantially intersected by a plane that contains the axis of the contact drum; and
    - 3. tiltable relative adjustment between the hinge axis of said hinged arm and the axis of the contact drum in directions parallel to said plane that substantially intersects the work zone, to enable said hinge axis and the axis of the contact drum to be brought into true parallelism or to be inclined to one another in said directions;
    - D. means for effecting such tilting adjustment;
    - E. yieldable force applying means arranged to effect relative work feeding motion between said work support and the contact drum, said yieldable feed

- force applying means comprising a hydraulic pressure responsive device connected with a pressure source; and
  - F. means for cushioning sudden increases in the feed force manifested at the engagement between the workpiece and the abrasive belt resulting from transient high spots in the workpiece surface and/or hard spots therein, said cushioning means comprising control valve means which is sensitive to changes in the force manifested at the engagement between the workpiece and the abrasive belt and operable to govern connection of the hydraulic pressure responsive device with its pressure source.
- 61.** The abrading machine of claim **60**, further characterized by:
- means for arresting relative feeding motion between the contact drum and the work support when a workpiece on the work support has been abraded to a predetermined level.
- 62.** The abrading machine of claim **60**, wherein the mounting structure further comprises
- means for effecting tilting adjustment of the contact drum.
- 63.** An abrading machine having a main frame and an endless abrasive belt trained over a horizontally oriented contact drum as its work performing element, and comprising:
- A. a work support having a work supporting surface to which a workpiece may be secured;
  - B. a supporting arm for the work support;
  - C. means rotatably mounting the work support on its supporting arm for rotation about an axis perpendicular to its work supporting surface;
  - D. hinge means mounting said supporting arm for swinging motion about an axis parallel to that of the contact drum between a lowered position in which the work supporting surface is substantially horizontal and an upright position in which the axis of the work support perpendicularly intersects the axis of the contact drum medially of its ends;
  - E. power means for imparting work feeding motion to the work support when the arm is in its upright position to feed a workpiece thereon against the contact drum-supported abrasive belt; and
  - F. drive means for rotating the work support about its axis while a workpiece thereon is being fed against the abrasive belt.
- 64.** The abrading machine of claim **63** wherein said hinge means comprises a hinged frame member mounted to swing about the hinge axis of the hinged arm in unison with said arm; and means to secure said frame member in an upright position; and further characterized in that said power means for imparting work feeding motion to the rotatable work support comprises fluid pressure responsive means reacting between said hinged frame member and said hinged arm.
- 65.** The abrading machine of claim **64** further characterized by a carriage slidably mounted on the main frame of the machine for translation perpendicularly towards and from the contact drum; wherein the common hinge axis of said hinged arm and hinged frame member is fixed with respect to said carriage so that translation of the carriage provides for adjustment of the distance between the work receiving surface of the rotatable work support and the

contact drum to adapt the machine to different sized work; and means for effecting translation of the carriage; and further characterized in that said means for securing said hinged frame member in its upright position comprises latch means on said carriage engageable with said hinged frame member.

66. The abrading machine of claim 59, wherein said means for bringing the rotatable work support into cooperative relation with said different grit abrasive belt means does so individually and successively, so that a workpiece can be successively abraded by the different grit size belt means without removing it from the rotatable work support.

67. The abrading machine of claim 66, wherein the different grit size belt means are supported on and driven by a single contact drum; and wherein said means for bringing the work support into cooperative relation individually with the different grit size belt means provides for relative displacement between the work support and the contact drum along a path generally parallel to the axis of the contact drum.

68. The abrading machine of claim 66, wherein the different grit size belt means are supported by a plurality of contact drums that are disposed in tandem spaced parallel relationship; and

wherein said means for bringing the work support into cooperative relation individually with the different grit size belt means provides for relative displacement between the work support and said plurality of contact drums along a path generally normal to the axes of the contact drums.

69. An abrading machine comprising:

A. a turntable mounted to rotate about a fixed axis;

B. a plurality of contact drums rotatable about fixed axes normal to the axis of the turntable with their peripheries tangent to a single plane spaced from and generally parallel to the turntable, said contact drums being equispaced from the axis of the turntable;

C. an abrasive belt trained over each contact drum, said belts being of different grit size;

D. a plurality of rotatable work supports, each adapted to have a workpiece attached thereto;

E. means mounting each of the rotatable work supports on the turntable with their axes parallel to that of the turntable and equispaced therefrom a distance such that upon indexed rotation of the turntable the work supports are successively brought into cooperative relation with the contact drums, so that a workpiece on a work support can be successively fed against the different abrasive belts without removing it from the work support to which it is attached;

F. said means for mounting the work supports on the turntable comprising arms hinged at one end to the turntable and having the work supports rotatably mounted on the other ends thereof;

G. yieldable biasing means reacting between each arm and the turntable to feed the workpiece on its respective work support successively against each of the abrasive belts with a force not exceeding a predetermined magnitude; and

H. power means for rotating the work supports while the workpieces thereon are being fed against the abrasive belts.

70. A surface abrading machine of the type comprising a power driven endless abrasive belt having a stretch thereof supported by a backup member engaging the back side of said belt, a work support member upon which a workpiece is held to be abraded by the belt and which is rotatable on an axis that substantially perpendicularly intersects the zone of contact between the workpiece and the abrasive belt, one of said members being movable toward and from the other to provide for engagement and disengagement between the workpiece and the belt and for relative feeding motion between the belt and the workpiece as abrasion takes place, said machine being characterized by:

means for exerting upon said one member a substantially large feed force in the feeding direction by which relative feeding motion of said one member toward the other is effected and which force is imposed upon the engaged surfaces of the workpiece and the belt to cause abrasion of the workpiece, said last named means comprising:

A. a force producing means arranged to react between said one member and a relatively fixed part of the machine;

B. means operatively associated with said force producing means to provide yieldability in its application by which an increase beyond a predetermined magnitude in the resistance the workpiece presents to being abraded is compensated and the feed force maintained constant;

C. means for achieving said motion producing means to thereby effect said relative feeding motion; and

D. means unaffected by discontinuity in contact between the workpiece and the belt resulting from interruption in the workpiece surface being ground, for controlling the rate at which said relative feeding motion occurs.

71. The surface abrading machine of claim 70 wherein said force producing means comprises a hydraulic cylinder, one end of which is connected with source of hydraulic pressure and its other end is connected with a hydraulic fluid reservoir during the production of said feed force; and

wherein said means for controlling the rate at which said relative feeding motion occurs comprises a flow control valve connected between said other end of the cylinder and the fluid reservoir.

72. The surface abrading machine of claim 70, wherein said force producing means comprises a screw and nut connection between said one member and said relatively fixed part of the machine; and wherein said means for controlling the rate at which said relative feeding motion occurs comprises means for regulating relative rotation between the screw and nut.

73. A surface abrading machine of the type comprising an endless abrasive belt trained over a contact drum member, a work support member upon which a workpiece is held to be abraded by the belt and which is rotatable during work performing engagement between the workpiece and the abrasive belt on an axis substantially perpendicular to that of the contact drum member and intermediate the ends thereof, one of said members being movable toward and from the other to

provide for engagement and disengagement between the workpiece and the belt and for relative feeding motion between the belt and the workpiece as abrasion takes place, said machine being characterized by:

- A. hinged arm means having said movable one of said two members mounted thereon; 5
- B. rigid frame structure to which said hinged arm means is hingedly connected for swinging movement about an axis substantially parallel with the axis of the contact drum member, to and from a position at which said two members are in cooperative relationship enabling a workpiece held by the work support member and the contact drum member-supported abrasive belt to be brought into engagement; 10
- C. force applying means arranged to react between said rigid frame structure and the hinged arm means for effecting work performing engagement between the workpiece and the abrasive belt; and 15
- D. means providing yieldability in said force applying means for cushioning sudden increases in the feed force manifested at the engagement between the workpiece and the abrasive belt and resulting from transient high spots in the workpiece surface and/or hard spots therein. 20

74. The surface abrading machine of claim 73, wherein it is the work support that is mounted on the hinged arm means.

75. The surface abrading machine of claim 73, wherein said means for providing yieldability in said force producing means comprises a closed air chamber having resiliently deformable wall means and containing air under pressure, and through which said force producing means acts. 30

76. The abrading machine of claim 73, wherein said force applying means comprises a hydraulic pressure responsive device connected with a pressure source, and 35

wherein said means for providing yieldability in said force producing means comprises control valve 40 means which is sensitive to changes in the force manifested at the engagement between the workpiece and the abrasive belt and operable to govern connection of the hydraulic pressure responsive device with its pressure source. 45

77. The abrading machine of claim 19, wherein said endless abrasive belt means comprises a plurality of abrasive belts, each having a stretch thereof supported

wherein there are a plurality of work supporting members, each of which meets the definition of the work supporting member set forth in claim 19, and further characterized by:

means for selectively bringing each work supporting member into cooperative relationship with all of said plurality of abrasive belts, so that a workpiece on any one of said rotatable work supporting members can be successively abraded by the plurality of abrasive belts without removing the same from its rotatable work supporting member.

78. A surface abrading machine comprising:

- A. a plurality of power driven endless abrasive belts, each having a stretch thereof supported by a backup member engaging the back side of the belt;
- B. a plurality of work supporting members, each of which has means for holding a workpiece to be abraded and for rotating the workpiece thereon about an axis that substantially perpendicularly intersects the zone of contact between the workpiece and the endless belt engaged by the workpiece;
- C. means for selectively bringing said work supporting members into cooperative relationship with said abrasive belts, so that workpieces on said work supporting members can be successively or simultaneously abraded by different abrasive belts;
- D. power drive means for effecting relative work feeding motion between a work supporting member and the backup member of the abrasive belt with which said work supporting member has been brought into cooperative relationship;
- E. means forming a feed rate controlling connection between said members comprising a screw having a force imparting connection with one of said members and a nut threaded on the screw and having a force imparting connection with the other of said members, so that relative work feeding motion between said members is possible only upon relative rotation in one direction between the screw and nut; and
- F. means for effecting such relative rotation so that the rate of said relative work feeding motion is governed by the rate at which said relative rotation between the screw and nut takes place.

UNITED STATES PATENT OFFICE
CERTIFICATE OF CORRECTION

Patent No. 3,816,998 Dated June 18, 1974
Inventor(s) Howard W. Grivna et al.

It is certified that error appears in the above-identified patent and that said Letters Patent are hereby corrected as shown below:

In the Abstract, line 4, "supprt" should read -- support --. Column 1, line 35, "abrasing" should read -- abrading --; line 42, after "is mounted" insert -- for movement --. Column 2, line 57, "view" should read -- views --. Column 4, line 8, "drum" should read -- drums --; line 34, "one" should be inserted before "end". Column 5, line 38, "mouted" should read -- mounted --; line 63, "releases" should read -- release --. Column 7, line 7, "tha" should read -- the --. Column 8, line 47, "drumsupported" should read -- drum-supported --; line 62, "feeling" should read -- feeding --. Column 9, line 17, place quotation marks around "loaded". Column 11, line 53, "and" should read -- an --. Column 13, line 28, "cylinder" should read -- cylinders --; line 34, delete "pressure compensated"; line 41, after "latter" insert --, which is pressure compensated, --; line 46, delete "pressure compensated"; line 54, "round" should read -- ground --; line 57, "is" should read -- if --. Column 14, line 28, place quotation marks around "Kisses" Column 15, line 32, "121" should read -- 121" --. Column 19, line 20, "falt" should read -- flat --. Column 21, line 26, before "for" insert -- and --; line 32, "out" should read -- about --. Column 28, line 47, "amy" should read -- may --. Column 33, line 10, "size" should be inserted after "grit". Column 34, line 33, "achieving" should read -- activating --. Column 36, line 6, "selective" should read -- selectively --; line 29, "abrasvie" should read -- abrasive --. Figure 21 should appear as shown on the attached sheet.

Signed and sealed this 1st day of April 1975.
